UNITED STATES PATENT OFFICE.

PATRICIA M. WILLIS, OF SAN FRANCISCO, CALIFORNIA.

PROTECTOR SPREADER FOR UMBRELLAS.

Application filed January 5, 1927. Serial No. 159,070.

My invention relates to spreaders especially adapted for canopies of the folding-frame type, and particularly for umbrellas and parasols.

5 An umbrella when not in use is set aside in folded condition; that is to say, its frame is collapsed and its cover hangs in folds, loosely about it. For longer periods of disuse, or for the sake of neatness when carried 10 about, the folds of the cover are usually compressed into small compass, by coiling pressure about the collapsed frame. In any case, the repeated, and often long continued partial or complete collapse of the umbrella 15 tends to wear the cover in the creases of its folds, so that it often happens that an umbrella, otherwise in good condition, may be injured as far as its cover is concerned, long before the real period of its normal life is 20 reached.

The object of my invention is to prevent this wear and injury to the cover; and to this end my invention consists in a novel 25 frame having a hub adapted for an encircling fit about the collapsed spreading links of the folding frame, and a periphery comprising an annular series of lobes adapted to enter the folds of the cover and hold their 30 creases spread.

30 In the accompanying drawings, to which reference is made, I show my protector spreader as constructed of a continuous piece such as a wire, but it is to be understood that this is only one structural instance of 35 the device, and which, for several reasons, may be a preferred form, though the device, obviously may be stamped out of sheet metal or otherwise made, such changes being within the knowledge of those skilled in the art; 40 and they may be made without departing from the spirit of my invention as defined by the claims appended hereto.

In the drawings:—

Fig. 1 is a perspective view of my device. 45 Fig. 2 is a horizontal section on the line 2—2 of Fig. 3, when the device is applied to an umbrella.

Fig. 3 is a vertical section of the same.

Fig. 4 is a detail view showing the wire secured hub laps of the lobes. 60

The device comprises a central annular hub or ring 1 and radiating lobes 2.

As shown clearly in Fig. 2 it may be made of a continuous wire progressivelylapping in the hub or ring center and extending radially on each side of the lap to form the lobes. The laps are retained by light wires 55 1' as indicated in Fig. 4. 3 is the umbrella staff; 4 are the spreading ribs; and 5 are the spreading links of the skeleton frame of the 60 umbrella. Indicated in dotted lines is the cover 6 of the umbrella. The ring 1 of my 65 protector spreader, when the umbrella frame is collapsed, fits over the lower portion of the link series 5 and is held in place thereon by frictional contact with the divergent links, which by their normal tendency to spread 70 insures, for all practical purposes, the positional stability of the device. The lobes 2 of the spreader extend outwardly between 75 the ribs 4 of the umbrella frame, and into the folds of the cover 6, thus holding said folds distended and preventing injurious creasing.

I claim:—

1. In combination with the staff, spreading ribs, spreading links and cover of an umbrella, a cover-protector frame comprising an annular hub fitting around said spreading links and an annular series of 80 lobes projecting radially from said hub into the cover to spread its folds. 75

2. In combination with the staff, spreading ribs, spreading links and cover of an umbrella, a cover-protector frame comprising a single continuous flexible member bent to form an annular hub fitting around said spreading links, said member successively lapping upon itself in the periphery of the hub and thence extending to form an annular series of radial lobes projecting into the 85 cover to spread its folds. 90

In testimony whereof I have signed my name to this specification.

PATRICIA M. WILLIS.
